UNITED STATES PATENT OFFICE

2,480,456

PISTON RING GROOVE CLEANER AND
DEEPENER

Houston Ellison, Tulsa, Okla.

Application March 23, 1944, Serial No. 527,796

2 Claims. (Cl. 82—4)

1

This invention relates to tools for cleaning the grooves of piston rings, and if necessary for deepening said grooves.

It has for its primary object the provision of a simple and effective tool wherein the working pressure of the scraper element of the tool may be finely adjusted so as to insure effective removal of the carbon gum or other solidified deposits adhering to the grooves of the piston ring, while at the same time avoiding the danger of digging or cutting into the metal of the piston, the latter being usually composed of a relatively soft metal.

A further object of the invention comprises the provision of an improved and simplified piston cleaner, it being pointed out that the prior piston cleaners are usually provided with adjustable tool carriers sliding along straight guides, bars, rods, or the like, said tool carriers requiring a plurality of adjustments to bring the scraping tool into correct position with respect to pistons of different size.

In accordance with the present invention, the sliding adjustment devices of the prior art tools are replaced by pivoted means requiring only a single adjustment to bring the scraper or cutter element of the tool into a central working position on pistons of varying diameters.

A further object of the invention comprises providing a simple and effective means for effecting the adjustment of the scraper element in its proper working position with respect to the piston, as well as the fine and precise adjustment of the working pressure.

Other objects and advantages of my invention will be apparent from the following specification.

The invention will be described in connection with the accompanying drawings, wherein

Figure 1 is a front elevational view of the tool;

Figure 2 is a side elevation thereof;

Figure 3 is a plan view partially in section taken along the line 3—3 of Figure 1;

Figure 4 is a longitudinal cross sectional view of the scraper disc mounting taken on the line 4—4 of Figure 1;

Figure 5 is a front elevational view of a modified form of the tool;

Figure 6 is a side elevation thereof;

Figure 7 is a longitudinal cross sectional view taken on the line 7—7 of Figure 6, and shows the mounting and locking of the scraper disc;

Figure 8 is an elevational detail of said parts; and

Figures 9 and 10 are details of the locking

2

mechanism which effect the locking of the scraper disc.

The piston groove cleaners of the prior art are provided with a single scraper or cutter disc attached to an arm which is itself attached to a flexible band or cord drawn around the piston and tightened so as to firmly grip the latter in order to bring the scraper into its correct working position relative to the piston grooves of varying diameters. These piston groove cleaners frequently consist of a straight portion and a bent or gooseneck portion integral therewith, the former serving as a guide for a slide carrying guide post on which the tool carrier proper is 15 slidably mounted. The latter usually consists of a slideable base member on which is mounted a disc provided with a plurality of scraper and/or cutter elements of varying sizes. It is necessary to adjust the scraper disc carrier on its slide post, and the slide post must be adjusted on the straight guide arm in such a manner that one of the scraper or cutter elements of the disc enters the groove of the piston to be cleaned on one side while the gooseneck or bent portion is 20 pressed against the piston on the other side. As it is not possible to secure a finely adjusted working pressure between the scraping tool and the piston in this manner, springs have been provided either between the scraper disc and the base or on additional intermediate parts which are pressing the scraper towards the work piece.

The piston cleaning tool, in that form of the invention shown in Figures 1 to 4 inclusive, is provided with a main body portion 1, to which 35 there is joined the bent gooseneck portion 2, said members being provided respectively with legs 2a and 2b, which are pressed against the piston 4 as shown in Figure 1, and form counter supports for the scraper or cutter element 10. The leg members are provided with ribs 3 of reduced cross section, as shown in Figure 3, said legs fitting into the grooves 4a of the piston. The scraper disc 9, which is provided with scrapers or cutters 40 10, is mounted on a carrier bar 8 pivotally connected with the body portion 1 of the tool by means of a pivot 7. The body portion 1 of the tool is provided with a tubular extending member or sleeve 6, the latter serving as a handle for the manipulation of the tool. The lower portion 45 of the sleeve 6 is interiorly provided with screw threads which cooperate with and are engaged by corresponding threads on the screw spindle 5, the latter being provided at its outer end with a milled or knurled knob or disc 13 for the purpose of manipulating the screw spindle. A push 50 55

bar member 11 is slidably mounted in the sleeve 6, and the lower end of the push bar member is in contact with the screw spindle 5. The other end of the spindle protrudes from the upper portion of the sleeve 6 and engages a pressure lug 12 projecting downwardly from the lower portion of the carrier bar 8. Instead of using a separate screw spindle 5 and an independent push bar 11 to move the carrier bar 8, these elements may be integral.

A spring 14 of any suitable type, but preferably a leaf spring, is inserted between the tool bar carrier 8 and the body portion 1 and is normally positioned to press the carrier bar outwardly, thereby holding the pressure lug 12 of the carrier bar permanently and firmly in contact with the upper end of the pusher bar 11. The scraper disc 9 carrying scrapers or cutter elements 10 is rotatably mounted on the forward end of the carrier bar 8 by any suitable means, as, for example, a pin 15, the latter being screwed into the upper end portion of the inwardly projecting bracket 17 of the bar 8, said pin serving as a shaft around which the scraper disc 9 may freely turn. The pin is held against longitudinal movement by the nut 16. The disc 9 consists of a number of scrapers, each preferably of different size and width, said scrapers projecting radially from a hub member, said scrapers enabling the tool to be used with pistons and piston grooves of varying diameters. Where a great variety of pistons are to be serviced, several scraper discs may be held in stock. When necessary, the scraper disc may be removed by unscrewing the pin from its seating member. A scraper or cutter 10 in its operative working position is locked or fixed immovably facing the leg member 2 of the goose-neck body portion, the latter providing means for engaging the piston at spaced points. To so hold and lock the scraper element 10, one of the idle scraper elements projects into a holding and locking member 19, preferably made by recessing the forward end of the locker bar 18, said locking member being provided with jaws 20, which are positioned at an acute angle to each other to form a wedge-like member engaging the idle scraper element 10. The jaws 20 are held in pressure contact with the idle scraper 10 by means of a spring acting on the lower surface of the locker bar 18, said spring operating in the bore 22 of the carrier bar 8. The locker bar 18 fits tightly in the bore 22 and its jaws 20 project beyond the upper end of the bore walls. The jaws 20 seize and grip firmly without play the idle scraper element 10 when it is moved into engagement with the locker bar. To unlock the locker bar 18 a thumb pin 23, shown as a small screw, is fixed to the locker bar 18, said pin projecting outwardly from a slot 24 provided in the wall of the bore 22 of the carrier bar 8. The upper end of the slot 24 serves as a stop preventing the locker bar 18 from moving further when the movement of the thumb pin is arrested by said end member.

The scraper element 10 may be brought into working position on pistons of varying diameter, having grooves of varying depth and width, by turning the knob 13 of the screw 5, thereby moving the carrier bar 8 with the scraper disc 9 around the pivot 7. The location of the pivot 7, acting as a fulcrum, is such that during the adjusting movement the working edge of the scraper element 10 moves along a line A—A which lies within a central section defined between the lines B—B and C—C, as shown in Figure 1. This

section approximately defines the central zone within which the angle of the attack of the cutting edge of the scraper element 10 on pistons of varying diameter remains within certain limits, and the cutter working within a part of the piston groove contained within said zone therefore operates under favorable working conditions on pistons of all sizes.

In using the tool, the operator proceeds in the following manner: After having selected and fixed the scraper disc 9, the knob 13 is turned so as to move the carrier bar 8 outwardly for a sufficient extent to permit the insertion of the scraper and cutter element 10 in the groove 4a of the piston. The proper scraper and cutter element for the piston groove may be selected before or after insertion. If selected after insertion, the operator depresses the thumb pin 23 and retracts the locker bar 18, and then turns the scraper disc 9 until the proper scraper element is in position opposite the groove to be operated on. When the correct scraper or cutter element has been selected, the operator then locks the idle scraper disc 10, thereby locking the active cutting and scraper disc 10 into position. Thereafter, to bring the active scraper element 10 into working position whereby it will scrape and/or cut the deposit which is to be removed from the piston groove, the knob 13 is again turned, thereby causing the scraper element to enter the piston groove and to penetrate the deposit which is to be removed. The operator may adjust the working pressure to be applied very finely by paying attention to the resistance which is encountered during adjustment. When the screw has been adjusted, the tool is then used in the usual manner. If the resistance encountered during the cleaning is too heavy or too slight, the pressure applied may be easily readjusted.

In the modification illustrated in Figs. 5 to 10 inclusive, the tool comprises a main body portion 1 and, preferably integral therewith, a bent portion or gooseneck portion 2, the lower portion of the body member being provided with a tubular extension 6, the latter being provided with screw threads which engage a screw 5 carrying a milled head or knob 13. Mounted on a carrier bar 25 is a scraper disc 9 provided with scraper or cutter elements 10. The carrier bar 25 is pivotally connected to the body member 1 by means of levers 28 and 29 and pivot pins 26, 27, 30 and 31 respectively, said levers being arranged in substantial parallelism to each other, forming, together with the carrier bar 25, a lever parallelogram providing a parallelogram means by which the scraper disc 9 and its scraper elements 10 may be moved towards the gooseneck portion 2.

The arrangement of the guiding members of the carrier bar is such that the cutting edge of the scraper 10 moves along a curved line A—A which is contained within the sector defined between the lines B—B and C—C. This sector, as explained in connection with Figure 1, defines the zone within which working conditions for pistons of different and varying sizes are most favorable and are approximately similar. A spring 32 is connected with one of the levers, as, for example, the lever 28, while the other lever is provided with a pressure boss 32a against which the end face 5a of the screw 5 abuts. The spring 32 functions to move the lever system away from the work piece and into pressure contact with the screw member 5. The scraper element 10 may be brought into operative position relative to the piston groove

containing a deposit to be removed by appropriate operation of a screw 5.

The scraper disc 9 is mounted on the carrier bar 25 by means of a pin 33 which is provided with a head 34 which abuts adjacent the outer surface of the scraper disc and with a screw-threaded portion 35 which projects into a bore 36 which is threaded to engage the screw threads of the screw member 35. The disc 9 is loosely mounted on the pin 33 and therefore may be revolved by the operator at will. However, the disc may be brought into a fixed position in accordance with the wishes of the operator. In order to firmly hold the disc and any cutter element in operative position, the disc is provided with holes 37 adapted to receive a locking pin 38 having a head 39. One hole is provided for each scraper position. The locking pin 38 is caused to enter into the hole 37 by the operation of a shield member 40 provided at its upper portion with a depending bent flange 41 having a slot 41a adapted to receive the locking pin 37. The shield 40, which preferably is in the shape of a shoe, partly surrounding the carrier bar 25, is pivoted thereon by a pivot 26 passing through the lateral flanges of the shield. This shield serves as a thumb piece, and its front end holding the pin 38 is permanently urged towards the carrier bar and the scraper disc by a spring 45. The pin 38 operates in the bore 38a in the upper portion of the carrier bar 25.

If the operator desires to change a scraper or cutter element 10, the operator presses on the rear part of the shield 40 serving as a thumb piece and thereby retracts the locking pin from the hole 37. While the pin is in the retracted position, the scraper disc can rotate around the shaft 33. All of these operations may be carried out with the fingers of the hand which holds the tool. The operation of the device is thought to be clear from the above description.

The piston groove cleaner tool of the present invention is a simple and effective instrument having a number of advantages over the prior art tools. By combining the adjustment of the scraper position and the adjustment of the working pressure to be used during the operation and by eliminating linear adjustments which are now most frequently used to bring the scraper into operative position, only a single fine and precise adjustment is needed, and thereby all complicated means for limiting the working pressure

or for holding it constant are dispensed with. The use of a screw impinging on a pressure boss results in greater precision and permits transmission of the strain through pressure surfaces.

5 What is claimed is:

1. In a device of the kind described, a carrier bar, an offset bracket projecting from one side of the carrier bar, a scraper disc mounted on said bracket and revoluble thereon, said disc having 10 radially extending cutters, and spring pressed latching means mounted in said carrier bar and adapted to engage one of said cutters and thereby hold a second cutter in operative position, said spring pressed latching means including a plunger projectable from the carrier bar and having a V-shaped notch in its upper end adapted to fit any one of said cutters, and a spring beneath said plunger urging the same upwardly.

2. In a device of the kind described, a carrier 20 bar, an offset bracket projecting from one side of the carrier bar, a scraper disc mounted on said bracket and revoluble thereon, said disc having radially extending cutters, said cutters being arranged in diametrically opposite pairs, and spring 25 pressed latching means mounted in said carrier bar and adapted to engage one cutter of a pair and thereby hold the opposite cutter in operative position, said spring pressed latching means including a plunger projectable from the carrier 30 bar and having a V-shaped notch in its upper end adapted to fit any one of said cutters, and a spring beneath said plunger urging the same upwardly.

HOUSTON ELLISON.
